[57] CLAIM

The ornamental design for an electric plug lockbox, a shown and described.

DESCRIPTION

FIG. 1 is a top, front, and left side perspective view of the inner cylinder portion of an electric plug lockbox showing my new design, the outer cylinder being omitted for clarity of illustration, the right side being identical to the left, and the bottom and rear being identical to the top and front, respectively;

FIG. 2 is a top, front, and left side perspective view of the outer cylinder portion thereof, with the inner cylinder portion being omitted for clarity of illustration;

FIG. 3 is a bottom, rear, and right side perspective view of the outer portion thereof with the inner cylinder portion being omitted for clarity of illustration; and,

FIG. 4 is an enlarged top, front, and left side perspective view thereof, showing both portions assembled.

FIG. 1

FIG. 2

FIG. 3

FIG. 4
